PREOILING SYSTEM

Arnold L. Couty, Marshfield, Oreg.

Application July 9, 1938, Serial No. 218,435

8 Claims. (Cl. 123—196)

This invention relates to a preoiling device for internal combustion engines.

It has been proposed to supply oil to the cylinders of internal combustion engines by forcing oil from the lubricating system of the engine to said cylinders.

In this type of construction the engine must be in full operation to create the oil pressure so that the oil is not supplied to the cylinders at the starting of the engine. It also has been proposed to supply the engine cylinders with an additional quantity of oil from a reservoir, but again the oil entering the reservoir is under varying pressures and the oil in this instance is not supplied to the cylinders when the engine is started cold.

An object of this invention is the provision of a preoiling system for the cylinders of internal combustion engines whereby a predetermined quantity of oil is maintained in a position so that it can be supplied to the cylinders of an engine upon the initial starting of the engine, the reservoir for storing the oil being under atmospheric pressure under normal conditions.

Another object of the invention is the provision of a device for supplying the cylinders of an internal combustion engine with a predetermined quantity of oil in which the oil is stored in a reservoir and drawn into the cylinders by the suction of the engine, a float closing a discharge port when all of the oil has been withdrawn from the reservoir while closing an air port when the reservoir has been completely filled with oil.

A further object of the invention is the provision of an oiling device for the cylinders of internal combustion engines whereby oil will be supplied directly to the cylinders when said cylinders are cold and when the engine is started, the device including a reservoir which is adapted to be supplied with oil either from the oil supply of the engine or from a separate source, a valve controlling the amount of air admitted to the oil receptacle, while a float valve restricts the amount of air admitted to the engine cylinders, the discharge of oil to the engine cylinders being under the control of a valve which is either operated manually or automatically in connection with some other operating mechanism of the engine.

This invention will be best understood from a consideration of the following detailed description, in view of the accompanying drawing forming a part of the specification; nevertheless, it is to be understood that the invention is not confined to the disclosure, being susceptible of such changes and modifications as define no ma-

terial departure from the salient features of the invention as expressed in the appended claims.

In the drawing,

Figure 1 is a side view in elevation of an engine showing my device attached thereto.

Figure 2 is a vertical section taken on the line 2—2 of Figure 3.

Figure 3 is a view in elevation of the device shown in Figure 2.

Figure 4 shows a modified form of the invention.

Referring more particularly to the drawing, 10 designates an internal combustion engine having any number of cylinders to which is connected an intake manifold 11 and an exhaust 13 manifold 12.

An air inlet pipe 13 is in communication with the intake manifold 11 and is controlled by means of a choke valve 14. This choke valve is actuated by a lever 15 and a rod 16 in any approved manner.

A casing 20 has a flanged top portion 21 upon which is mounted a cover plate 22. This cover plate is secured to the casing 20 by means of bolts 23. The lower end of the casing is reduced 25 as shown at 24. Beyond this reduced portion is a threaded nipple 25 which is screwed into an opening 26 formed in the intake manifold 11.

The casing 20 is provided with an oil chamber 30, an air chamber 31 and a passage 32 leading from the oil chamber through the threaded nipple 25 into the intake manifold 11.

An elongated valve 35 is slidably mounted in a passage 36 in the reduced portion 24 and extends across the passage 32 and normally closes 38 the same. A packing 37 and a gland 38 prevent the loss of fluid from the passage 36.

A spring 40 has one end engaging a depending arm 41 of a bracket 42 which is secured at 43 to the casing 20. The other end of the spring 40 abuts a disc 44 held in place on the valve or rod 35 by means of a pin 45.

The outer end of the rod 35 is provided with an elongated slot 46 which is adapted to receive one end 47 of a rod 48. This rod extends downwardly as shown in Figure 1 and is connected to the free end of the choke lever 15. A rod 49 is connected at 50 to the outer end of the rod 35 and extends to the dash for manual manipulation by the operator of the car.

A pipe 51 projects through the side wall of the casing 20 and into the chamber 30. This end of the pipe is sealed against the loss of fluid by means of a gland 52 and a packing 53. The other end of the pipe as shown in Figure 1 ex-

tends downwardly to an oil pump 54. On the other hand, a reservoir or storage tank may be employed, as shown in Figure 4. In this instance, a tank 55 is supported by the cylinder block in 5 any approved manner and the pipe 51 extends from the bottom of the tank.

A float valve 56 is located in the chamber 30 and rises with the level of the oil in said chamber. When the chamber is empty said valve will 10 rest upon the bottom of the chamber as shown in dotted lines in Figure 2. This float valve is provided with a central restricted passage 57 for a purpose which will be presently explained.

The closure 22 is provided with a cup-shaped 15 member 60 having a pocket 61 forming a part of the air chamber 31 and in this pocket is mounted an air valve 62 in the form of a float which is adapted to close the port 63 in the cup-shaped member 60. A cotter pin 64 has legs 65 which 20 supports the valve 62 in the cup-shaped member 60. The weight of the valve 62 is sufficient to maintain said valve open except under certain conditions.

A gasket 66 and a gland 67 seal one end of a 25 pipe 68 in the side wall of the reduced portion 24. This pipe opens into the passage 32. The other end of the pipe 68 is carried to the motors of a windshield wiper and this connection forms a convenient means for connecting the windshield wiper with the intake manifold.

The operation of my device is as follows: The 30 chamber 30 is normally filled with oil so that when the valve 35 is operated either by the rod 49 or the connection 48 with the choke valve, the 35 valve will open the passage 32 and allow the lubricant in the chamber 30 to flow through the passage 32 to the intake manifold 11, whence the lubricant is conducted to the cylinders of the internal combustion engine.

40 When the lubricant has been emptied from the chamber 30 the float valve 56 will seat upon the top of the passage 32 and close the same so that no more oil will be drawn into the engine cylinders. If the valve 35 is operated manually the 45 operator of the car will close the valve after the engine has started. On the other hand, when the choke has been closed on starting the engine the valve 35 will be opened but it will be closed automatically when the choke is again 50 opened.

The oil chamber 30 will fill up with oil and be 55 ready at all times for supplying the cylinders with additional lubricant when the engine is started, or when it is deemed necessary to supply the cylinders with pre-lubricant particularly when the engine is cold. Since the valve 62 is normally open air will escape from the chamber 31 to permit the oil entering said chamber to rise.

The air vent or passage 63 is only closed by the 60 valve 62 when the oil in the chamber 30 rises sufficiently for the purpose. At this time the float valve 56 will also engage the bottom of the closure plate 22. When the oil is lowered in the chamber 30 the air valve 62 will open the chamber 65 to atmosphere. Any excess oil in the chambers 30 and 31 will flow back through the pipe 51 and back to its source after the engine has been stopped. However, the operation of the engine will maintain the chamber 30 filled with 70 oil.

The vent 57 in the float valve 56 will permit 75 just enough air from the chamber 31 to enter the passage 32 above the valve 35 when the oil has been emptied from the chamber 30 and said float valve is resting upon the bottom of said

chamber to break the vacuum or suction pressure against the float valve so that the float will rise as the chamber 30 is being filled with oil and after the valve 35 has been closed.

The diameter of the passage 32, as shown in 5 Fig. 2, is comparatively greater than the diameter of the pipe 51 so that when the valve 35 is opened the oil in chamber 30 will pass rapidly to the intake manifold 11 by means of suction and gravity and said chamber will be emptied before oil 10 through the restricted tube 51 will tend to fill said chamber.

The air valve 62 permits free passage of air 15 to and from the chamber 31 until it is closed by the sufficient rise of the oil in said chamber.

The upper end of the rod 48 has a loose connection at 47 with the valve rod 35 by means of the slot 46 so that the rod 49 can reciprocate the valve 35 independently of the choke valve 14 due to the fact that the angular disposed portion 20 47 of the rod 48 can move back and forth in the slot 46 without causing operation of the choke. The diameter of the pipe 51 is such that when it is connected to the tank 53, oil will not be drawn into the tank faster than it is drawn off 25 thereby permitting valve 56 to seat after the body of oil in the chamber 30 has been discharged.

I claim:

1. A preoiling device for the cylinders of internal combustion engines having an intake 30 manifold, comprising a housing provided with a chamber for lubricating oil and a passage in the bottom thereof connecting the chamber with the manifold, means connecting the chamber with an oil supply, a float valve adapted to be lowered 35 for closing the passage when oil has been emptied from the chamber, a manually operated valve controlling the admission of oil to the manifold, means for operating the last-mentioned valve.

2. A preoiling device for the cylinders of internal combustion engines having an intake manifold, comprising a housing provided with a chamber for lubricating oil and a passage in the bottom thereof connecting the chamber with the manifold, means connecting the chamber adjacent the top with an oil supply, a float valve closing the passage when the oil has been emptied from the chamber, a manually operated valve controlling the admission of oil to the manifold, means for operating the last-mentioned valve, 40 said housing having an air vent for admitting air to the chamber above the oil and a valve for closing said vent when the oil rises sufficiently in the chamber.

3. A preoiling device for the cylinders of internal combustion engines having an intake manifold, comprising a housing provided with a chamber for lubricating oil and a passage connecting the chamber with the manifold, means connecting the chamber with an oil supply, a float valve closing the passage when oil has been drawn from the chamber, a valve controlling the admission of oil to the manifold, means for operating the last-mentioned valve, the float valve 45 having a restricted air opening for breaking the vacuum in the passage to permit the float valve to rise when oil is admitted to the chamber.

4. A preoiling device for the cylinders of internal combustion engines having an intake 70 manifold, comprising a housing provided with a chamber for lubricating oil and a passage connecting the chamber with the manifold, means connecting the chamber with an oil supply, a float valve closing the passage when oil has been 75

drained from the chamber, a manually operated valve controlling the admission of oil to the manifold, means for operating the last-mentioned valve, a choke valve operating rod and 5 means connecting the operating means for the last-mentioned means with said choke valve operating rod.

5. A preoiling device for the cylinders of internal combustion engines having an intake 10 manifold, comprising a housing provided with a chamber for lubricating oil and a passage connecting the chamber with the manifold, means connecting the chamber with an oil supply, a float valve closing the passage when oil has been 15 drained from the chamber, a manually operated valve controlling the admission of oil to the manifold, means for operating the last-mentioned valve, a choke valve operating rod, means connecting said choke valve operating rod with the 20 last-mentioned means, said connecting means including means to permit independent manual operation of the controlling valve.

6. A preoiling device for the cylinders of internal combustion engines having an intake 25 manifold and a choke valve comprising a housing having a chamber therein, a passage connecting the chamber with the manifold and an air inlet opening, means connecting the upper end of the chamber with an oil supply, a valve controlling 30 said opening, a manually operated oil discharge valve controlling the flow of oil through the passage to the manifold, means for actuating the choke valve, means connecting the last-mentioned means with the oil discharge valve and 35 means for actuating the oil discharge valve independently of the actuating means for the choke valve.

7. A preoiling device for the cylinders of internal combustion engines having an intake manifold and a choke valve comprising a housing having a chamber therein, a passage connecting the chamber with the manifold and an air vent, 5 a float valve closing said passage when oil is drained from the chamber, means having a restricted opening and connecting the chamber with an oil supply under pressure, an oil discharge valve controlling the flow of oil through 10 the passage connecting the chamber with the manifold, means for actuating the choke valve, means connecting the last-mentioned means with the oil discharge valve, and means for actuating the oil discharge valve independently of 15 the actuating means for the choke valve.

8. A preoiling device for the cylinders of internal combustion engines having an intake manifold and a choke valve comprising a housing having a chamber therein, a passage connecting 20 the chamber with the manifold and an air inlet opening, means connecting the upper end of the chamber with an oil supply, a valve controlling 25 said opening, an oil discharge valve controlling the flow of oil through the passage to the manifold, means for actuating the choke valve, means connecting the last-mentioned means with the oil discharge valve and means for actuating the oil discharge valve independently of the actuating 30 means for the choke valve, a float valve in the 35 chamber and closing the passage when the oil has been withdrawn from said chamber, said float valve being provided with a restricted opening to relieve suction on said valve.
